F. E. CARDULLO

HOUSING FOR PLANERS

Filed Feb. 23, 1923

INVENTOR:

Forrest P. Cardelle

BY
George Keller
ATTORNEYS.

UNITED STATES PATENT OFFICE.

FORREST E. CARDULLO, OF CINCINNATI, OHIO, ASSIGNOR TO THE G. A. GRAY COMPANY, OF CINCINNATI, OHIO.

HOUSING FOR PLANERS.

Application filed February 23, 1923. Serial No. 620,837.

To all whom it may concern:

Be it known that I, FORREST E. CARDULLO, a citizen of the United States, residing at Cincinnati, in the county of Hamilton and State of Ohio, have invented Improvements in Housings for Planers, of which the following is a full, clear, and exact description, reference being had to the accompanying drawing, forming part of this specification.

10 My invention relates to metal planers and has to do with methods of attaching the saddle for the side head, and the cross rail, to the housings.

The purpose of this invention is to provide a more secure and free moving attachment for the side head saddle, and to secure a more rigid method of attaching the cross rail, whereby the thickness of the rail where it is subject to bending and torsion is increased, and the length of that portion of the rail subject to such action is diminished.

Among other things a standard or housing is provided in which the form of groove therein is designed to accommodate both the side head and the rail in the advantageous manner noted.

I accomplish my objects by that certain construction and arrangement of parts to be hereinafter more specifically pointed out and 30 claimed.

In the drawings:

Figure 1 is a section through the housings of a planer above the cross rail, taken in a horizontal plane.

35 Figure 2 is a section through one of the planer housings and the saddle of a side head, also taken in a horizontal plane.

Figure 3 is a front elevation partially diagrammatic of a planer, showing the location of the frame parts involved in this invention.

Referring to the drawings, *a* is a portion of the right hand, and *b* is a portion of the left hand, housing of a planer. *c* is the saddle of a side head which slides vertically upon the front face of the housing *a*, below the rail. In order to insure true and accurate motion of the saddle *c*, and to keep it from springing away from the housing at any point, under the action of the working forces, it is formed with a hook or dovetail projection *c*¹ which fits into a corresponding dovetail groove formed at the inner edge of the front face of the housing. The faces

of this groove are *a*¹ and *a*², and the saddle *c* is held in firm sliding contact with these faces by means of a gib *d* which abuts against surface *a*⁴.

The surface *a*⁴ is a smoothly machined surface formed in the groove *a*³ and parallel with the intersection of surfaces *a*¹ and *a*². Surface *a*³ is slightly relieved so that there is clearance between the housing and the saddle at this surface. The saddle is held in firm sliding contact with the housing face at *a*⁵ by means of the gib *e* which engages the surface *a*⁶ machined on the rear of a tongue or ledge formed at the outer edge of the housing face. This ledge is bounded by surfaces *a*⁵, *a*⁶, and *a*⁷.

Gib *e* is held in place by clamp *f* which is fastened to the saddle by stud *g* and nut *h*. This construction enables me to hold saddle *c* in firm sliding contact with housing *a* at the extreme inner and outer edges of the housing face, so that it can not spring away from the housing face when working forces are applied to it. At the same time by placing gib *d* so that it is in contact with surface *a*⁴ instead of with surface *a*⁷, the saddle is guided in a vertical direction much more easily, since the two guiding surfaces *a*² and *a*⁴ are much closer together.

The groove included between *a*¹ and *a*² is designed also to accommodate the cross rail in the manner to be noted, and thus a single housing construction doing double duty is provided, which housing provides advantageous mounting possibilities for the saddle and the rail as well.

Between the housings *a* and *b* is cross rail *i*. This cross rail instead of being of usual form is provided with two step-like projections *i*¹ and *i*² which bear against faces *a*² and *b*¹ of the dovetail grooves formed in housings *a* and *b*. At the inner side of each housing is a tongue or ledge by means of which the rail is clamped to the housing. On one side of each of these ledges is machined a clamping surface *a*⁸ and *b*⁸. Against these clamping surfaces bear clamps *j* and *k*, held tightly in place by studs *l* and *m*, and nuts *n* and *o*. The rail is thus clamped tightly to the ledge, the rail bearing against surfaces *a*² and *b*² and the clamps against surfaces *a*⁸ and *b*⁸.

My improvements consist in providing the projections *i*¹ and *i*², by means of which

the rail bears against the housing, instead of having the rail bear against the front faces of the housings at a^3 and b^3 or a^5 and b^5 . By this means the length of the rail subject 5 to bending and twisting is reduced to the distance indicated by the line A instead of the distance indicated by the line B, as is the case were projections i^1 and i^2 to be omitted, or some greater distance when the 10 rail is clamped only to the outer ledges of the housings. Furthermore the thickness of the rail at the point of clamping is increased from the thickness indicated by the line D to the thickness indicated by the line C, and 15 the rail thereby made much stronger as well as stiffer.

Having thus described my invention, what I claim as new and desire to secure by Letters Patent, is:—

- 20 1. In a metal planer, a vertical housing having a dovetail groove formed at the inner edge of the face thereof and a bearing surface machined in a second groove in the face of the said housing and parallel with the said dovetail groove, a saddle adapted to slide upon the said housing and having a dovetail projection adapted to engage the said dovetail groove, and a gib sliding with the saddle upon the said machined surface, 25 and adapted to draw the dovetail projection of the saddle into firm sliding contact with the said dovetail groove.
2. In a metal planer, a vertical housing having a dovetail groove formed at the inner edge of the face thereof and a bearing surface machined in a second groove in the front face of the said housing and parallel with the said dove-tail groove, a saddle adapted to slide upon the said housing and 30 having a dove-tail projection adapted to engage the said dove-tail groove, a gib sliding with the saddle upon the said machine surface, and adapted to draw the dove-tail projection of the saddle into firm sliding contact 35 with the said dove-tail groove, and a second gib sliding with the saddle and adapted to draw the saddle into firm sliding contact with the front face of the housing near its outer edge.
3. In a metal planer, a vertical housing having a dove-tail groove formed at the inner edge of the face thereof whereby the housing is adapted to receive the dove-tail of a sliding saddle, a cross rail having a step-like projection one face of which is adapted 45 to engage one face of the said dove-tail groove and a clamp on the cross rail engaging the housing at a point thereon which

60 pulls the cross rail bearing on the groove into tighter engagement therewith.

4. A housing for planers, and a side head and cross rail associated therewith, comprising a housing having a dovetail groove along the inner edge of the face thereof, a side head having a dove-tail projection to fit said groove, and a cross rail having a projection adapted to lie against the one face of the dove-tail groove only, and the groove so cut, that it removes part of the corner of the 65 housing, whereby said projection on the cross rail does not dovetail into the said groove.

5. A housing for planers and a cross rail associated therewith, comprising a housing having a groove cut in the inner edge of the 70 face thereof, said groove removing part of the adjacent corner of the housing, a cross rail, bearing against the housing, and having a projection engaging the one face of said groove, and a clamp on the cross rail engaging the housing at a point thereon which 75 pulls the cross rail bearing on the groove into tighter engagement therewith.

6. A housing for planers and a cross rail associated therewith, comprising a housing having a projecting ridge extending along its inner face and having a bearing face directed substantially parallel with the cross rail, and a cross rail having a projection to lie along said parallel bearing face, and to 80 engage the housing at other points parallel with said bearing face and to engage the inner face of said housing projection, and a clamp on the cross rail adapted to engage the housing at another point in a direction 85 opposing the said bearing face, whereby the said projection of the housing is engaged at one side by the clamp and at the other by the cross rail.

7. A housing for planers, and a side head and cross rail associated therewith, comprising a housing having a dovetail groove along the inner edge of the face thereof, a side head having a dovetail projection to fit said groove, and a cross rail having a projection 90 adapted to lie against one face of the dove-tail groove only, and the groove so cut, that it removes part of the corner of the housing, whereby said projection on the cross rail does not dovetail into the said groove, and means on the rail and side head to engage the housing at another point to maintain their respective engagements with said 95 groove.

FORREST E. CARDULLO.
